UNITED STATES PATENT OFFICE.

HARRY C. TILLOTSON, EARL A. RULLISON, AND CHARLES W. MCKINLEY, OF TOLEDO, OHIO, ASSIGNORS TO THE TILLOTSON MANUFACTURING CO., OF TOLEDO, OHIO, A CORPORATION OF OHIO.

CARBURETOR.

Application filed March 31, 1922. Serial No. 548,271.

This invention relates to improvements in carburetors, having reference particularly to the fuel supply for idling.

In carburetor practice, it is quite customary to provide an idling nozzle for supplying fuel to the engine when the throttle valve is closed or nearly closed, or in idling position, at which time the main nozzle is ineffective. In carburetors of this character the vacuum affecting the idling nozzle decreases very rapidly as the throttle is opened. This reduces the flow of mixture to the idling nozzle and coupled with the excess of air admitted by the throttle produces a mixture too lean to give satisfactory results. Until the engine attains a certain speed, equivalent to from six to ten miles an hour vehicle speed for certain motor vehicles, the suction is insufficient to draw a charge from the main nozzle around which the vacuum is not very great because the flow of air around the nozzle necessarily is not much restricted. At such engine speeds, therefore, the engine will fail to run satisfactorily, this phenomenon being called frequently a "spot." One of the objects of this invention is the provision of means to eliminate such "spots."

Another difficulty often met with is the failure of the carburetor to provide a sufficiently rich fuel mixture at times when it is desired to apply a load to the engine more or less suddenly, as when the speed of the vehicle is to be accelerated. Auxiliary wells in which a reserve of fuel is collected to be drawn upon only during acceleration of the engine have been frequently utilized for the purpose of overcoming this difficulty. Another object of this invention is the provision of a means of this character which is so arranged and constituted that at high engine speed the richness of the mixture is automatically reduced or at any rate not increased, thus effecting economy in operation at high speed.

Other objects of the invention relating to details of construction and economies of manufacture will appear as we proceed with the description of that embodiment of the invention which for the purposes of the present application we have illustrated in the accompanying drawing in which:

Figure I is a vertical section taken through the middle of the nozzle and carbureting chamber and through the float bowl.

Figure II is a vertical sectional detail view taken substantially on the line II-II, Fig. I.

Fig. III is a central, vertical, sectional view of the main nozzle on a large scale, showing clearly the details of construction.

Similar reference characters refer to like parts throughout the views.

In the drawing, the numeral 10 indicates the casing of the carburetor proper while 11 is the float bowl having a cover 12. In the casing 10 there is a horizontal air inlet portion 13 controlled by a choke valve 14 and a vertical mixing chamber 15 containing the usual venturi 16 and throttle valve 17. The attaching flange 18 may be integral with the upper portion of the casing.

A nozzle device arranged axially of the mixing chamber is formed preferably of three concentric spaced tubes 19, 20 and 21. From an inspection of Fig. III in particular, it will be noted that the inner tube 19 is spaced uniformly from the intermediate tube 20. Intermediate tube 20 however, includes an enlarged middle portion 22 running entirely around the periphery whereby there are formed in effect three different cylindrical spaces between the intermediate and outer tubes 20 and 21 respectively. The middle cylindrical space is extremely narrow. A measurement of about one-one hundredth inch on each side has been found to be satisfactory. This space is too minute to be shown on the small scale of Fig. I.

The lower cylindrical space between the tubes 20 and 21 is connected with the space between the tubes 19 and 20 by a port 23 through the tube 20. The upper end of the same tube has a series of perforations 24 lying substantially in the plane of the surface of the fuel in the float bowl. It has been found that these openings may be a little above that level without materially affecting the operation of the carburetor. Another series of ports 25 through the inner tube 19 are located at some little distance above the normal fuel level. The outer tube 21 is provided with a series of ports 26, preferably eight in number, located above the ports 24 thus producing a series of fuel sprays around the periphery of the nozzle in order to assist in breaking up the mixture into fine particles.

The manner of mounting the three tubes 19,

20 and 21 may be varied so long as means are provided for properly centering the tubes and for sealing the lower extremities of the intermediate and outer tubes. The means illustrated in the drawing is satisfactory from a manufacturing as well as from an operative standpoint. In the structure shown the outer tube 21 is provided with a peripheral collar 27 adapted to fit closely within the smooth 10 inner portion of an opening 28 extending upwardly from the bottom of the casing 10. When the parts are assembled, this collar 27 bears against a packing ring 29 which rests in turn, against an annular shoulder over- 15 hanging the opening 28. The outer tube is forced into position and held there by engagement at its lower extremity with a flange 30 on the end of the intermediate tube 20. This flange is conical on its lower side for 20 engagement with a conical surface on an externally threaded nut 31. In this manner assembly of the tubes is much facilitated, since the middle tube is centered and the middle and outer tubes forced into position and held 25 there by the tightening of the single nut 31.

The nut 31 is provided with a central orifice of sufficient size to accommodate the tube 19 and to provide a cylindrical passage around the exterior thereof. The tube 19 is tightly 30 mounted at its lower end in a nut 32 whereby it is centered and held in position. The upper ends of the tubes are fitted tightly one into the other.

The main fuel passage of the carburetor 35 comprises a short vertical bore 33 leading downwardly from the float bowl into a bore 34 of larger diameter. A calibrated plug 35 connects these two bores. Plugs 35 having different sized openings therethrough may 40 of course be employed interchangeably, or other means for accomplishing the same end, such for instance, as an adjustable valve, may be substituted if desired. A horizontal bore 36 connects the vertical bore 34 with a space 45 37 between the nuts 31 and 32, the bore 36 being interrupted intermediate its length by a vertical screw threaded bore 38.

Just above the bottom of the tube 21 there are relatively large openings 39 communicating with a peripheral passage around the exterior of the tube 20, which in turn communicates with an auxiliary fuel well consisting of the horizontal portion 40 and the vertical portion 41, the latter being a bore concentric 55 with the bore 38 and opening thereinto. The two bores 38 and 41 are connected by a calibrated plug 42 which is provided on its upper side with a conical surface adapted to center and form a tight joint with the lower end of 60 a by-pass tube 43 which protrudes through the casing at the upper end of the bore 41 and connects with a small chamber or passageway 44 having an air inlet 45 arranged to be opened to a greater or lesser extent by a 65 conical or needle valve 46 threaded into the

casing and provided with a thumb piece 47. The chamber 44 is connected with the mixing chamber 15 by means of two vertically spaced ports or outlets 48 and 49 the upper one of which is always open and the lower one of 70 which is open only when the throttle shutter 17 is open more or less. The upper end of the auxiliary fuel well 40 and 41 above the fuel level has constricted communication with the atmosphere through a calibrated plug 50. 75 The parts 51, 52, 53, 54 and 55 are merely threaded plugs for closing the ends of the bores into which they are fitted.

Operation.

80

When an engine to which this carburetor is attached is idling, fuel passes from the float bowl through bore 33, calibrated plug 35, bores 34, 36 and 38, calibrated plug 42, by-pass tube 43, chamber 44 and port 48 into the mixing chamber 15, and thence into the engine manifold, the fuel when it reaches the chamber 44 being mixed with air coming through the passage 45. It is characteristic of this arrangement for supplying the fuel mixture 85 for idling purposes that the liquid fuel is drawn from a point beneath the normal level of the fuel in the float bowl and free from admixture with air prior to its delivery to the chamber or passageway 44. The delivery of fuel to chamber 44 and its mixture with air at that point is, of course, dependent upon the engine demand through the port 48 alone or in conjunction with 49 as the position of the throttle 17 over the latter may permit. As 90 the throttle 17 is opened slightly, port 49 as shown is also immediately or progressively uncovered, whereupon a larger quantity of mixture is led into the manifold. This quantity of explosive mixture is sufficient to insure satisfactory operation of the engine until the throttle 17 is opened far enough to make the main nozzle fully effective thus avoiding 95 spots.

Fuel for the main nozzle is delivered 100 through the passages 33, 34 and 36 into the space 37 and then upwardly between the tube 19 and the nut 31 into the cylindrical space between tubes 19 and 20, passing upwardly as far as ports 24. Here it meets a downwardly moving cylindrical column of air coming from the open lower end of the tube 19 upwardly through that tube and through the ports 25 at the upper end thereof. This provision for causing a downward flow of air to meet an upward flow of fuel results in the air holding back the flow of fuel so that instead of the usual increase in the proportion of fuel to air ratio as engine speed increases, a constant or diminishing ratio is maintained as more air 115 is drawn through the venturi.

Air and fuel pass together through the ports 24 being thereby commingled to a greater or lesser extent. This mixture is then caused by engine suction to move upwardly 120

130

into the cylindrical space between the upper portion of tubes 20 and 21 and then out through the numerous holes 26, thereby being broken up into a fine vapor which mingles 5 intimately with the air passing rapidly through the venturi surrounding the nozzle.

At the same time that the suction of the engine causes the flow of gas just described, suction becomes effective through the ports

10 26 and the restricted cylindrical passage between the two outer tubes 20 and 21 to reduce the pressure in the auxiliary well 40, 41. While this well is in communication with the atmosphere through the restricted opening 15 in the calibrated plug 50 the latter opening is not large enough to maintain atmospheric pressure in the well when the latter is subjected to the suction effect referred to. The low pressure in this well assisted by gravity 20 causes fuel to flow through the port 23 in the intermediate tube 20 and through openings 39 into the well. The relative amount of suction effective to lift fuel into the auxiliary well is dependent upon the amount of clearance 25 between the tubes 20 and 21 and upon the size of the hole in the plug 50.

At any given engine speed, if the throttle of a carburetor is suddenly closed or nearly closed, the vacuum in the manifold is increased 30 above the vaporization point of the fuel and all the liquid in the manifold is vaporized. Unfortunately the reverse is also true, that is, if the throttle is suddenly opened, liquid is thrown out of the mixture 35 in the manifold and wets the walls of the latter, resulting in an impoverishment of the mixture. To make up this impoverishment it is necessary to supply a temporarily rich mixture during acceleration. This is accomplished 40 in the present instance by drawing upon the supply of fuel in the auxiliary wells 40, 41. When the throttle is opened suddenly, producing an increased suction effect upon the nozzle, the fuel begins to flow 45 out of the auxiliary well to the upper end of the nozzle, up between the two outer tubes, also possibly directly through the hole 23 and up between the two inner tubes.

Our apparatus is designed as to the restricted space between the two outer tubes 20 and 21 and as to the size of the opening in calibrated plug 50, so that when a certain predetermined speed is reached and exceeded, the flow of fuel through the port 23 and 55 openings 39 into the auxiliary well is not only reversed, but the supply of fuel in the auxiliary well is exhausted to such an extent that air begins to flow through the plug 50 and auxiliary well up through the port 23, and also through the restricted space between 60 the two outer tubes 20 and 21, thus tending to reduce still further the richness of the mixture at high engine speeds.

In a few words, therefore, certain important 65 features of our invention consist in means

for obtaining the result that when a small volume of air passes through the venturi, the auxiliary well fills to a certain level with fuel, and upon sudden opening of the throttle, this fuel is drawn out of the auxiliary well 70 to supply the necessary enrichment of the mixture, while thereafter, if a comparatively high speed is maintained, air is bled through the plug 50 and auxiliary well, giving a highly desirable thinning-out effect. 75

While we have described more or less in detail a specific embodiment of our invention, it is to be understood that the foregoing showing and description are illustrative only and for the purpose of making the disclosure of 80 the invention thoroughly clear and understandable. We do not regard the invention as limited to the details of construction illustrated or described herein, except in so far as we have included such limitations within the 85 terms of the following claims, in which it is our intention to claim all novelty inherent in the invention broadly as well as specifically.

Having thus described our invention, what 90 we claim as new and desire to secure by Letters Patent, is:

1. In a carburetor; a main nozzle; a mixing chamber; a throttle valve therein; a fuel supply for said nozzle; a liquid fuel by-pass 95 from said fuel supply; means for admitting a calibrated quantity of air to said by-pass; a port from said by-pass above said throttle valve in the idling position of the latter, and a second port from said by-pass into said 100 mixing chamber substantially closed by said throttle valve against intake into said by-pass in said idling position but beyond said throttle when the latter is opened slightly whereby an additional quantity of mixture 105 from said by-pass is admitted to said mixing chamber.

2. A carburetor having a main nozzle; a fuel supply for said nozzle; a main mixing chamber; means for throttling mixture flow 110 to the engine; an auxiliary mixing passageway; a separate auxiliary liquid fuel delivery means from said fuel supply for said auxiliary mixing passageway; means for admitting air to said auxiliary liquid fuel; outlet 115 means from said auxiliary passageway arranged to discharge into said mixing chamber when said throttle is in idling position; and additional outlet means from said auxiliary passageway, said latter means being sub- 120 stantially closed against intake therethrough, by said throttling means in said idling position, but opened to discharge from said auxiliary passageway when said throttle is opened from said idling position. 125

3. A carburetor having a main nozzle; a fuel supply for said nozzle; a main mixing chamber; means for throttling mixture flow to the engine; an auxiliary mixing passageway; an auxiliary liquid fuel orifice connect- 130

ed to be supplied with liquid fuel from said fuel supply; auxiliary air admitting means for said auxiliary liquid fuel; outlet means from said auxiliary passageway arranged to 5 discharge into said mixing chamber when said throttling means is in idling position; and additional outlet means from said auxiliary passageway, said latter means being rendered inactive to discharge of mixture into 10 said main mixing chamber when said throttling means is in said idling position, but rendered active to discharge from said auxiliary passageway when said throttle is opened from said idling position; and common means for 15 adjusting said auxiliary air supply for regulating the mixture ratio issuing from both outlet means.

4. A carburetor having a main nozzle; a fuel supply for said nozzle; a main mixing 20 chamber; means for throttling mixture flow to the engine; an auxiliary mixing passage-

way; an auxiliary liquid fuel delivery means from said fuel supply for said auxiliary mixing passageway; means for admitting air to said auxiliary liquid fuel; means for admitting air into said main nozzle; outlet means from said auxiliary passageway arranged to discharge into said mixing chamber when said throttle is in idling position; and additional outlet means from said auxiliary passageway; said latter means being substantially closed against intake therethrough by said throttling means in said idling position but opened to discharge from said auxiliary passageway when said throttle is opened from 35 said idling position.

In testimony whereof, we affix our signatures.

HARRY C. TILLOTSON.
EARL A. RULLISON.
CHARLES W. McKINLEY.
